UNITED STATES PATENT OFFICE.

JOHN OLIPHANT, OF CHICAGO, ILLINOIS, ASSIGNOR TO SULLIVAN MACHINERY COMPANY, A CORPORATION OF MASSACHUSETTS.

PUMPING SYSTEM.

Application filed May 8, 1922. Serial No. 559,395.

My invention relates to pumping systems, and more particularly to pumping systems of the displacement type.

An object of my invention is to provide an improved pumping system. Another object of my invention is to provide an improved pumping system of the displacement type. A further object of my invention is to provide an improved pumping system of the multiple unit displacement type having improved controlling mechanism. Other objects and advantages of my invention will appear in the course of the following specification and appended claims.

15 In the accompanying drawings I have shown for purposes of illustration one form which my invention may assume in practice.

In these drawings,—

20 Fig. 1 is a diagrammatic plan view of a pumping system employing the illustrative form of my invention.

Fig. 2 is a central vertical section through one of the control valves and the operating mechanism therefor.

25 Fig. 3 is an elevation of one form of controlling mechanism which may be employed with my pumping mechanism.

Fig. 4 is a view likewise in elevation of the same mechanism, the view showing the parts 30 as if the entire mechanism were turned bodily about a vertical axis through 90 degrees.

Fig. 5 is a plan view of the mechanism shown in elevation in Figs. 3 and 4.

35 Fig. 6 is a vertical section taken on the broken line 6—6 of Fig. 5.

Fig. 7 is a section on the line 7—7 of Fig. 4.

40 For purposes of illustration I have shown my improved pumping system in a form adapted to the raising of relatively large quantities of cement slurry or other liquid material from a lower level to a considerably higher level by the use of relatively low air pressures. For the purpose of pumping this material, I employ herein a series of three batteries of displacement pumps. The material is pumped by these pumps, which will be later more fully described, from a tank A by means of a pumping unit B to a tank C; thence by a pumping unit D to a tank E and finally by a pumping unit F to its intended destination. It will be evident that a greater or smaller number of pumping units B, D and F, might be used if desired.

It will also be evident that it is unnecessary that the elevation of the several tanks successively increase as circumstances such as distance, viscosity of the fluid pumped, or other conditions may render it desirable to employ a series of pumps such as is shown herein. As all these units are similar, it will be sufficient to describe the unit B.

This unit comprises a pair of displacement tanks 1 and 2 connected respectively 45 by check valved connections 3 and 4 with the tank A and discharging to a line 5 respectively through check valved connections 6 and 7. Pumping fluid, herein compressed air, is applied alternately to the tops of these 50 tanks by way of lines 9 and 10, one of these lines operating for the supply of the pumping fluid, while the other is vented or, as shown herein, is connected to the suction side of the compressor supplying the pumping fluid. A valve mechanism generally 55 designated 11 and comprising a casing 12 in which a four-way valve 13 is oscillatable controls the connection with the lines 9 and 10 of a line 14 which leads to a connection 60 15 leading in turn to a receiver 16 which is supplied with air by a compressor 17. This valve 13 also controls the connection of the lines 9 and 10 with a connection 18 which 65 leads to a line 19 connecting with the suction side of the compressor 17, a valve 20 of well known form serving to supply further air to the compressor intake as may be necessary to keep the system filled. The valve 70 13 and the ports in the casing 12 are so arranged as to interconnect the tanks through lines 9 and 10 as the valve shifts, thereby 75 transferring air from one tank to the other. It will be noted that the lines 15 and 19 have branches 14 and 18 leading to each of 80 the several pumping systems. For the purpose of controlling the movements of the valves 13, I arrange servo motor-cylinders 21 adjacent the valve mechanisms 11 and 85 place in these cylinders pistons 22 whose piston rods 23 lead to cross heads 24 which are connected by connecting rods 25 with levers 26 which swing the valves 13. The 90 opposite ends of the servo motor-cylinders are connected to lines 27 and 28 which lead 95 to the opposite sides of a valve casing 29 (see Fig. 7) in which a four-way valve 30 is oscillatable. The casing 29 is also provided with a connection 31 leading to the 100 line 15 and with a connection 32 leading to 105 110

the line 19. It will thus be evident that lines 27 and 28 are alternately subjected to pressure and suction and so that the pistons 22 are alternately moved in opposite directions as pressure is supplied to one side thereof, while a partial vacuum is formed in the opposite ends of the cylinders 21. By reason of the design of the valve member 30 and the valve casing 29 the opposite ends 10 of the cylinder 21 are momentarily interconnected as the valve shifts. Since each of the pistons 22 is similarly connected to its valve 13, it will be apparent that each of the pumping systems B, D and F is simultaneously similarly controlled.

With the foregoing mechanism, as a unitary controller I employ a control mechanism which is the invention of one David H. Hunter and which serves to automatically reverse the position of the valve 30 at suitable intervals. This mechanism which is generally designated 50 comprises a pair of cylinders 51 and 52 of which the cylinder 51 is an operating cylinder and the cylinder 52 is a dashpot cylinder. Within the cylinder 51 is reciprocable a piston 53 to whose upper end is attached an L-shaped crosshead 54 and which carries above the crosshead a weight 55. Air may be supplied to the cylinder 51 by way of a port 56 from a pipe 57 controlled by an ordinary three-way valve 58, hereinafter referred to more in detail. Within the cylinder 52 is reciprocable a dashpot piston 59 connected by a rod 60 with the crosshead 54 whereby the dashpot piston 59 and the actuating piston 53 move simultaneously, the rate of movement of the actuating piston 53 being governed by the rate of possible movement 40 of the dashpot piston 59. To control the movements of the dashpot piston 59 there is arranged in the wall of the cylinder 52 a longitudinally extending port 61 which communicates with the interior of the cylinder by four ports, one arranged near the upper end of the cylinder and designated 62, one arranged substantially at the bottom and designated 63, and a pair near the middle of the cylinder separated by a short distance longitudinally of the cylinder, and respectively designated 64 and 65. An adjustable throttling screw 66 is arranged in the portion of the passage 61 which lies between the ports 64 and 65. It will be evident that the piston 59 may move rapidly on its upward travel until the port 65 is covered and must then move slowly as the liquid, herein oil, contained in the dashpot must be forced through the port 64 and around past the throttling screw 66 and through the port 65 until after the port 64 is passed and uncovered by the bottom of the piston and that thereafter the piston 59 may move rapidly, simply bypassing the oil through the port 62, passage 61, and port 64. It will be evi-

dent that also on the downward movement of the piston 59 it will move rapidly adjacent each end of its travel and be retarded at the middle of its travel. The three-way valve 58 previously referred to is adapted to control the communication of a connection 67 leading from the compressor, herein from the line 15, with the port 56 and in one position of said valve opens free communication between the line 67 and the port 56, while in another position it interrupts such communication and connects the port 56 with the atmosphere. As the construction of such valves is well known, no illustration is believed necessary, the ordinary T port, three-way valve being entirely satisfactory for this function. To control the movements of the valve 58 I have attached thereto an operating lever or arm 68 having oppositely extending arms, to one of which arms a spring 69 is attached, and the other of which is adapted to engage stops 70 and 71 formed on guides 72 and 73 in which an actuating rod 74 slides. To the rod 74 the spring 69 is attached at 75. The rod 74 is provided with adjustable collars or abutments 76 and 77 which are alternately engageable by the crosshead 54, through a hole in which the rod passes. It will be observed that as the rod 74 is raised to its upper position, the free end of the spring 75 will pass above the longitudinal axis of the arm 68 and that accordingly the valve 58 will be sharply reversed from the position shown in Fig. 4 to a position in which the supply of fluid to the port 56 will be cut off and the cylinder 51 vented. It will be noted that a similar mode of operation will occur upon the downward movement of the rod 74 and that accordingly the valve 58 has its position rapidly changed and that only at the ends of the paths of travel of the cross-head 54. It will be noted that the valve 30 is provided with an operating arm 78 to which is provided an actuating rod 79 having collars 80 and 81 secured thereto and that the crosshead 54 also engages these collars by reason of the fact that the rod 79 passes through an opening in the crosshead 54.

The mode of operation of this mechanism will be readily apparent. Assume the control valve 58 to be in the position shown. Fluid under pressure passing from the line 67 through the port 56 beneath the piston 53 will force the latter upward, the rate of upward movement being controlled by the possible rate of movement of the dashpot piston 59. When the piston 53 has moved upward to a sufficient extent the crosshead 54 will engage the collar 80 and reverse the position of the valve 30. The crosshead 54 will likewise engage the collar 76 and at the extreme upper end of the desired movement the piston 53 will cause the reversing of the position of the valve 58. This will result

in the downward movement of the piston 53 under the action of gravity due to its own weight and the weight 55, and the crosshead 54 near the lower end of its movement will 5 shift the valve 30 in the opposite direction and will again shift the three-way valve 58 at the extreme end of its travel. It will be evident therefore that the valve 58 is moved relatively rapidly when it is moving and 10 that the movement of the piston is so controlled by the dashpot that the valve 30 is maintained stationary during practically the entire period of fluid pressure supply to the pipes 27 and 28.

15 Now, it being understood that the control valve mechanism 50 is arranged so that its period between shifting of the valve 30 is such as to substantially empty the tanks 1 or 2 of the several displacement units B, D and 20 F, the mode of operation of the entire system will be readily apparent. Assume that the parts are in the position shown in Figs. 1 and 2. It will be evident that the several upper tanks, i. e. those shown toward the top 25 of the sheet and designated 1 will be emptying while the other tanks will be filling, i. e. the tanks 2, since the tanks 1 are being subjected to pressure from the line 15 and the tanks 2 are being connected with the reduced 30 pressure by way of the line 19. Upon shifting of the valve 30, it will be evident that the line 27 will no longer be connected to the line 15 by way of line 31 and that the line 28 will no longer be connected with the line 35 32 and so to the suction side of the compressor, but that these connections will be reversed and, by reason of the supply of pressure to the right hand sides of the pistons 22, while the pressure at the opposite 40 ends of the cylinders is reduced, the valves 13 will be shifted and each of the displacement pumping units B, D and F will begin to discharge the tanks 2, while the tanks 1 are subjected to a suction and thereby 45 enabled to fill rapidly. It will be clear that my pilot valve mechanism 30 controls a series of several motors simultaneously and that as a result a number of displacement units can be similarly controlled. It will accordingly be evident that I have provided 50 a much more economical system than would be possible were separate pilot valve controls used for each of the valves employed for switching the flow to the tanks and it will be further evident that a more uniformly working system is also provided, whereas, with separate controls each wholly independent of the others, there would be great difficulty in maintaining anything like 55 a uniform transfer of material along the system. It is to be observed, moreover, that by the use of relatively short connections of approximately uniform length between the various pumping units of the main discharge 60 lines there is more uniform working than

were fluid admitted directly to a pair of long lines which were alternatively vented and connected to the discharge side of a compressor.

Any surplus of air compressed by the compressor 17 and not needed in the system may be conducted from the receiver 16 by way of a line 90 through a check valve 91 to a receiver 92 therein to supplement the supply from a compressor 93 and to be used for any 75 purpose which may arise.

While I have in this application specifically described one form which my invention may assume in practice, it will be understood that this form of the same is shown for 80 purposes of illustration and that the invention may be modified and embodied in various other forms without departing from its spirit or the scope of the appended claims.

What I claim as new and desire to secure 85 by Letters Patent is:

1. In a displacement pumping system, a plurality of displacement pumping units each comprising at least two displacement tanks, means for supplying and exhausting 90 fluid to said tanks including separate control valves for each of said units, separate servo-motors each controlling one of said controlling valves, and a common pilot valve for controlling said several servo motors. 95

2. In a pumping system, a displacement tank, a connection with said tank for the supply of pumping fluid thereto, a valve controlling said connection, fluid operated means for actuating said valve, and fluid operated means controlling the flow of fluid to 100 said valve operating means separately operated by fluid from the same source as that supplied to said tank.

3. In a pumping system, a plurality of 105 displacement tanks, connections with said tanks for the supply of pumping fluid thereto, a separate valve for controlling each of said connections, a separate fluid operated device for actuating each of said valves, and a common fluid operated device controlling the flow of fluid to said valve operating devices and operated by fluid from the same 110 source as that supplied to said tank.

4. In a pumping system, a displacement 115 tank, connections between said tank and a source of liquid to be pumped and a point of discharge, a connection with said tank for the supply of pumping fluid and the exhaust thereof, a valve controlling said last mentioned connection, and means controlling said valve operated by the fluid from the same source as that supplied to said tank but wholly independent in its operation of 120 pressure variations in said tank and the fluid flowing to the latter being inoperative to effect any control of said valve. 125

5. In a displacement pumping system, a displacement tank, a pumping fluid supply line, a suction line, a connection with said 130

5 tank, a valve controlling the communication of said connection with said supply and suction lines, a servo motor controlling the movements of said valve, and means for subjecting said servo motor to the pressures in said supply and suction lines including a valve whose movements are independent of the fluid conditions in said connection.

10 6. In a displacement pumping system, a displacement tank, a pumping fluid supply line, a suction line, a connection with said tank, a valve controlling the communication of said connection with said supply and suction lines, a servo motor controlling the 15 movements of said valve, and automatic means for alternately connecting the opposite ends of said servo motor to said supply and suction lines and wholly independent in its operation of the fluid condition in said 20 connection.

25 7. In a displacement pumping system, a displacement tank, a pumping fluid supply line, a suction line, a connection with said tank, a valve controlling the communication of said connection with said supply and suction lines, a servo motor controlling the movements of said valve, and automatic means for alternately connecting the opposite ends of said servo motor to said supply and 30 suction lines and intermediately in communication with each other.

35 8. In a multiple displacement lift, a plurality of serially arranged sets of alternately operating pumps, valve means for connecting said pumps of each series alternately to pumping fluid supply and exhaust, servo motors each controlling one of said valves, and a single means for simultaneously controlling said servo motors.

40 9. In a multiple displacement lift, a plurality of serially arranged sets of alternately operating pumps, valve means for connecting said pumps of each series alternately to pumping fluid supply and exhaust, servo motors each controlling one of said valves, and common means for simultaneously controlling said servo motors by alternately connecting homologous ends thereof to supply and exhaust.

45 50 10. In a displacement pumping system, a plurality of displacement pumping units, pressure and exhaust lines extending into contiguity to each of said units, connections between each of said units and said pressure and exhaust lines, valve means controlling the communication between said connections and said units, and common means for controlling the operation of said several valve means.

55 60 11. In a displacement pumping system, a plurality of displacement pumping units, pressure and exhaust lines extending into contiguity to each of said units, connections between each of said units and said pressure and exhaust lines, valve means control-

ling the communication between said connections and said units, servo-motors one associated with each of said valve means, and common means for controlling the operation of said servo-motors and so of said several 70 valve means.

75 12. In a displacement pumping system, a plurality of displacement pumping units, pressure and exhaust lines extending into contiguity to each of said units, connections between each of said units and said pressure and exhaust lines, valve means controlling the communication between said connections and said units, and means for controlling the operation of said several valve means 80 including servo-motors one associated with each of said valve means, and means for connecting the opposite ends of each of said servo-motors alternately to supply and exhaust and, during changes in connection, to 85 each other.

90 13. In a displacement pumping system, a plurality of displacement pumping units, pressure and exhaust lines extending into contiguity to each of said units, connections between each of said units and said pressure and exhaust lines, valve means controlling the communication between said connections and said units, and means for controlling the operation of said several valve means 95 including servo-motors one associated with each of said valve means, and a single valve for connecting the opposite ends of each of said servo-motors alternately to supply and exhaust and, during changes in connection, 100 to each other.

105 14. In a displacement pumping system, a plurality of displacement pumping units, pressure and exhaust lines extending into contiguity to each of said units, connections between each of said units and said pressure and exhaust lines, each of said units including a pair of displacement tanks, valve means associated with each of said units for establishing alternate communications between each of said tanks and the connections to the supply and exhaust lines and intermediately, connections with each other, and means for effecting simultaneous shifting of 110 all of said valves.

115 15. In a displacement pumping system, a plurality of displacement pumping units, pressure and exhaust lines extending into contiguity to each of said units, connections between each of said units and said pressure and exhaust lines, each of said units including a pair of displacement tanks, valve means associated with each of said units for establishing alternate communications between each of said tanks and the connections to the supply and exhaust lines and, intermediately, connections with each other, and means for effecting simultaneous shifting of all of said valves including servo-motors 120 associated one with each of said valves.

16. In a displacement pumping system, a plurality of displacement pumping units, pressure and exhaust lines extending into contiguity to each of said units, connections 5 between each of said units and said pressure and exhaust lines, each of said units including a pair of displacement tanks, valve means associated with each of said units for establishing alternate communications between each of said tanks and the connections to the supply and exhaust lines and, intermediately, connections with each other, means for effecting simultaneous shifting of 10 all of said valves including servo-motors one 15 associated with each of said valves, and a common pilot valve controlling all of said servo-motors. 17. In a displacement pumping system, a plurality of displacement pumping units, 20 pressure and exhaust lines extending into contiguity to each of said units, connections between each of said units and said pressure and exhaust lines, each of said units including a pair of displacement tanks, valve means associated with each of said units for establishing alternate communications between each of said tanks and the connections to the supply and exhaust lines and, intermediately, connections with each other, means for effecting simultaneous shifting of 25 all of said valves including servo-motors one with each of said valves, and a common pilot valve controlling all of said servo-motors and operative to interconnect the opposite ends of said servo-motors between the connections thereof to pressure and exhaust. 30 35

In testimony whereof I affix my signature.

JOHN OLIPHANT.
